D. E. PAYNE.
FUR STRETCHER.
APPLICATION FILED MAY 7, 1919.

1,348,238.

Patented Aug. 3, 1920.

UNITED STATES PATENT OFFICE.

DAVID E. PAYNE, OF MAGNOLIA, MINNESOTA.

FUR-STRETCHER.

1,348,238.

Specification of Letters Patent.

Patented Aug. 3, 1920.

Application filed May 7, 1919. Serial No. 295,298.

To all whom it may concern:

Be it known that I, DAVID E. PAYNE, a citizen of the United States, residing at Magnolia, in the county of Rock and State of Minnesota, have invented certain new and useful Improvements in Fur-Stretchers; and I do hereby declare the following to be a full, clear, and exact description of the invention, such as will enable others skilled in the art to which it appertains to make and use the same.

The invention relates to a fur stretcher.

The object of the present invention is to improve the construction of fur stretchers and to provide a simple, practical and efficient device of strong, durable and comparatively inexpensive construction designed for stretching the furs of ermine, minks, weasels, musk-rats, skunks, civet-cats, etc., and capable of easy operation to stretch a fur without injuring the same.

With these and other objects in view, the invention consists in the construction and novel combination of parts hereinafter fully described, illustrated in the accompanying drawing and pointed out in the claims here-to appended; it being understood that various changes in the form, proportions, size and minor details of construction, within the scope of the claims, may be resorted to without departing from the spirit or sacrificing any of the advantages of the invention.

In the drawing:

Figure 1 is a side elevation partly in section of a fur stretching device constructed in accordance with this invention.

Fig. 2 is a longitudinal sectional view of the same.

Fig. 3 is an enlarged sectional view of the lower portion of the device illustrating the construction of the locking means.

Fig. 4 is a detail sectional view on the line 4-4 of Fig. 1.

Fig. 5 is a detail view illustrating the manner of slidably mounting the lower sections of the resilient frame.

Fig. 6 is a sectional view taken on the line 6-6 of Fig. 1.

Like numerals of reference designate corresponding parts in the several figures of the drawing.

In the accompanying drawing, in which is illustrated the preferred embodiment of the invention, the fur stretching device comprises in its construction a main central operating bar 1 provided at the upper end

with a ring 2 to enable it to be hung up or engaged with a hook to assist the operation of the device and provided at its lower end with a hand hold 3. The upper portion of 60 the bar 1 extends through a slot 4 in a resilient approximately inverted U-shaped frame 5 and is provided with stops 6 consisting of pins or keys and located at spaced points above and below the central portion 65 of the frame 5 to limit the relative sliding movement of the bar and the frame.

The bar and the frame are provided with eyes 7 and 8 to which are connected links 9 and 9', the lower links being slightly longer 70 than the upper links to provide for an increased spread of the lower portion of the frame.

The frame is equipped with slidable sections 10 and 11 of tubular formation forming continuations of the sides of the frame and slidably receiving the same. The sections 10 and 11 are provided with slots 12 through which extend the lower eyes 8 and the section 10 has its lower end 13 recessed 80 to receive one end of a spreader bar 14 which is pivoted at 15 in the recess of the section 10. The other section 11 is provided with a slot 16 through which the spreader bar 85 passes and the outer end of the spreader bar is preferably provided with a hand hold 17.

The relative longitudinal movement of the central bar and the frame is adapted to spread the frame which is locked in its adjustment by means of a pawl or dog 18 90 mounted in the lower end of the section 11 and arranged to engage notches 19 in the lower edge of the spreader bar 14, a spring 15 being preferably employed for maintaining the dog in engagement with the notches 95 19, but any other form of dog may of course be employed for this purpose.

The bar 14 extends through a slot 20 in the central bar, which is provided with notches 21 adapted to be engaged by a tooth 100 22 of a slide 23 preferably consisting of a loop of rectangular form and equipped with a set screw 24 which may be employed for securing it in engagement with the central bar.

The central bar is also provided at opposite sides with clamps 25 of approximately U-shape mounted in slots 26 of the bar 14 and provided with an adjusting screw or bolt 27 having a winged nut 28 for forcing the jaws of the clamps into engagement with 110 the bottom of the fur, but any other suitable clamp may of course be employed for this

purpose. The fur to be spread is placed over the frame, and in practice the device will be constructed to stretch a fur approximately three inches, but the size of the device may 5 be varied and the amount of stretching may of course be regulated by the locking devices.

What is claimed is:

1. A stretching device of the class described including a central bar, an approximately inverted U-shaped frame provided at the top with an opening slidably receiving the bar, links connecting the bar with the sides of the frame and arranged to swing to spread the said frame, a transverse spreader bar connected with the sides of the frame and having an adjustment with respect to one of the sides, and means for securing such spreader bar and sides 10 of the frame in their relative adjustment.
2. A stretching device of the class described including a central bar, an approximately inverted U-shaped frame provided at the top with an opening slidably receiving the bar, links connecting the bar with the sides of the frame and arranged to swing to spread the said frame, a transverse spreader bar pivotally connected with one side of the frame and extending through 15 the central bar and through the other side of the frame and adjusting means for securing the spreader bar to the central bar and to the side of the frame with which it is slidably connected.
3. A stretching device of the class described including a central bar, an approximately inverted U-shaped frame provided at the top with an opening slidably receiving the bar, links connecting the bar with the sides of the frame and arranged to swing to spread the said frame, a transverse spreader bar pivotally connected with one side of the frame and extending through the central bar and through the 20 other side of the frame, said central bar

and spreader bar being provided with notches, a slide mounted on the spreader bar for engaging the notches of the central bar, and a dog carried by the same for engaging the notches of the spreader bar. 50

4. A fur spreading device including a central bar, an approximately U-shaped frame slidably connected at the top with the central bar, links connecting the sides of the frame with the central bar, slidable 55 sections arranged on the sides of the frame and having slots through which certain of the links pass, a spreader bar extending through the central bar and pivoted to one of the sections and extending through the 60 other section, and means for adjustably securing the spreader bar to such section and to the central bar.

5. A fur spreader of the class described including a central bar, a frame connected 65 with the central bar, links connecting the central bar with the frame and arranged to spread the said frame, a spreader bar connected with the central bar and with the sides of the frame, and clamps carried by 70 the spreader bar for engaging the fur.

6. A fur spreader of the class described including a central bar, a frame connected with the central bar, links connecting the central bar with the frame and arranged to 75 spread the said frame, a spreader bar connected with the central bar and with the sides of the frame, said spreader bar being provided with slots, approximately U-shaped clamps operating in the slots for 80 engaging the fur and provided with adjusting means for maintaining them in such engagement.

In testimony whereof I affix my signature in presence of two witnesses.

DAVID E. PAYNE.
